(57) **CLAIM**

The ornamental design for a jack-clamp winch push adapter, as shown and described.

DESCRIPTION

FIG. 1 is a perspective view of the jack-clamp winch push adapter of the present invention.

FIG. 2 is a front elevation.

FIG. 3 is a top plan view.

FIG. 4 is a bottom plan view.

FIG. 5 is a view taken from the right side of FIG. 2 of the jack-clamp winch push adapter.

FIG. 6 is a rear elevation.

FIG. 7 is a side elevation taken from the right side of FIG. 6 of the jack-clamp winch push adapter; and,

FIG. 8 is a perspective view showing the environment of the jack-clamp winch push adapter.

The broken line showing of a jack in FIG. 8 is for illustrative purposes only and forms no part of the claimed design.
